UNITED STATES PATENT OFFICE.

HENRY WILLOCK RAVENSHAW, OF HANWELL, ENGLAND.

MAGNETIC CLUTCH.

942,186.

Specification of Letters Patent.

Patented Dec. 7, 1909.

Application filed February 28, 1907. Serial No. 359,905.

To all whom it may concern:

Be it known that I, HENRY WILLOCK RAVENSHAW, of Rutland House, Hanwell, in the county of Middlesex, England, have invented new and useful Improvements in Magnetic Clutches, of which the following is a specification.

My invention, by means of which increased efficiency in action is obtained, relates to magnetic clutches of that type in which an annular electromagnet attracts an annular keeper through an intermediate element consisting of two concentric rings of magnetic material attached to each other by a ring of flexible non-magnetic material so that the intermediate element may yield sufficiently to adapt its faces to those of the contiguous parts and to produce, in consequence, a tighter hold when in clutching position.

In order that my invention may be more readily understood I shall now refer, by way of types or examples, to certain forms thereof and these I illustrate in the accompanying sheets of drawings.

In the drawings,—Figure 1 is a central section of one form of my invention; Fig. 2 is a central section of a modification; Fig. 3 shows a detail; Fig. 4 shows an embodiment of my invention in which the driving and driven shafts are parallel; Fig. 5 shows a construction in which the magnetic circuit is completed through a sleeve; and Fig. 6 shows a construction in which the magnetic circuit is completed through the shaft.

Referring to Fig. 1, 1 is the annular trough of magnetic material mounted upon the spider 2 which is keyed to the driving shaft 3, and 4 is the energizing coil. 5 is a hood preferably of non-magnetic material fixed to the periphery of the annular trough 1. 6 is a flat ring of magnetic material feathered at its periphery to the hood 5 so as to rotate therewith but be capable of sliding to and fro in a direction normal to its plane. 7 is an intermediate element consisting of two concentric rings 8 and 9 of magnetic material attached to one another by the ring of flexible non-magnetic material 10. The element 7 is mounted upon the spider 11 which is feathered to the driven shaft 12 so as to slide longitudinally thereon. When current is transmitted through the energizing coil the elements 6 and 7 are pulled to the right and close up upon the

trough, the electromagnetic circuit being through the three elements as shown by the closed dotted line 13. The friction between the contacting surfaces which is largely increased by reason of the tight fit of the parts, made possible by the flexible non-magnetic ring 10, then causes the shaft 12 to be driven in the usual way.

In Fig. 2, I show a case which differs from that shown in Fig. 1 in that the number of working faces is increased still further, there being now four intermediate elements 7¹, 7², 7³, 7⁴, of which 7¹ and 7³ are slidably feathered on the shaft 12 and 7² and 7⁴ slidably feathered in the hood 5. In this case the element 6, instead of being feathered in the hood 5 as in Fig. 1, is slidably feathered on the shaft 12. In other respects this case is similar to that shown in Fig. 1 and the flexible non-magnetic ring again acts to produce a close and tight fit of the parts when closed on each other.

In Fig. 3, I show how the concentric rings 8, 9, may, through the intervention of the rivets 14, be connected together by the ring 10, preferably made of thin gun metal.

Fig. 4 illustrates a case which differs from those shown in Figs. 1 and 2 in that the driving and driven shafts, instead of being in alinement, are placed side by side. In this case it will be seen that there is no hood 5 but that instead thereof each alternate element gears with a long pinion 15 upon the driven shaft 12. In this case all the elements except the electromagnetic trough slide upon the driving shaft 3.

In Fig. 5, I illustrate a case which differs from those previously described mainly in that the magnetic circuit instead of being completed through the inner rings 9 is completed through a sleeve of magnetic material 16. In this case the intermediate elements 7¹, 7³ and 7⁵ instead of sliding on the shaft 12 slide upon and are feathered to the magnetic sleeve 16. The magnetic circuit is indicated by the closed dotted line 13 as before.

In Fig. 6, I show another case which differs from those previously described in that the magnetic circuit instead of being completed through rings 9, as shown in Figs. 1, 2 and 4, or through a sleeve of magnetic material, as shown in Fig. 5, is completed through the shaft as indicated by the line 110

13. This modification, specifically considered, is however claimed in another application filed March 29, 1909, No. 486,610.

5 I prefer to make the hood 5 of gun metal but I have found that I might even make it of magnetic material although that is disadvantageous.

It is obvious that I may combine two or more of the features hereinbefore specified.

10 Thus for example I could employ a sleeve 16 in the case where only a single intermediate element is employed as in Fig. 1. Or I might make the elements in Fig. 4 of such shape as to complete the magnetic circuit 15 through the driving shaft 3. Or I could place the driving and driven shafts parallel to one another with other forms of elements, and with other courses of magnetic circuits, than as shown in Fig. 4.

20 It will be obvious that the driving and driven shafts can be made interchangeable and that I might compose my clutch of an element fast on one shaft, an element loose on that shaft, one or more intermediate elements and a gear fast on the other shaft.

I claim,—

1. A magnetic clutch comprising a driving and driven shafts, an annular electromagnet and an annular keeper, and an intermediate element consisting of two concentric rings of magnetic material secured together by a flexible ring of non-magnetic

material, whereby a tighter fit between the parts of the clutch when in operation is effected, substantially as described.

35

2. A magnetic clutch comprising a driving and driven shafts, an annular electromagnet and annular keeper, an intermediate element consisting of two concentric rings of magnetic material secured together by a flexible ring of non-magnetic material, and a sleeve of magnetic material surrounding the shaft, the magnetic circuit from the magnet to the keeper being completed out through the intermediate element and back 40 through the sleeve, substantially as described.

3. A magnetic clutch comprising an annular electromagnet and an annular keeper, an intermediate element consisting of two 45 concentric rings of magnetic material secured together by a flexible ring of non-magnetic material, the outer ring being supplied with gear teeth, and a driving and a driven shaft one of which carries a pinion 50 meshing with the teeth described, substantially as described.

In witness whereof I have signed my name to this specification in the presence of two subscribing witnesses.

HENRY WILLOCK RAVENSHAW.
